UNITED STATES PATENT OFFICE.

SVEND E. JOHANNESEN, OF PITTSFIELD, MASSACHUSETTS, ASSIGNOR TO GENERAL ELECTRIC COMPANY, A CORPORATION OF NEW YORK.

TRANSFORMER.

1,323,770.

Specification of Letters Patent.

Patented Dec. 2, 1919.

Application filed August 24, 1916. Serial No. 116,636.

To all whom it may concern:

Be it known that I, SVEND E. JOHANNESEN, a citizen of the United States, residing at Pittsfield, county of Berkshire, State of Massachusetts, have invented certain new and useful Improvements in Transformers, of which the following is a specification.

My invention relates to transformers provided with taps whereby the voltage impressed on the load circuit may be varied; it relates particularly to transformers without moving parts for supplying constant current series circuits, or circuits adapted to receive substantially constant current and in which the devices constituting the load are connected in series. One object of my invention is to provide a method of changing the voltage impressed on a circuit by such devices as transformers without changing the per cent. reactance of such devices. Another object is to provide a transformer in which the number of active turns may be varied without materially changing its per cent. reactance. Other objects of my invention, broader than these, are to provide a method of varying the voltages supplied by such apparatus without the variations in voltage being accompanied by the changes of reactance (and per cent. reactance) heretofore unavoidable, and to provide apparatus for carrying out this method. Still other objects will appear hereinafter.

On the reactance of transformers expressed in per cent. of the open circuit secondary voltage, depends materially the decrease in secondary voltage with increase of current, the current on short circuit, and the effect of the transformer in determining the power factor of its primary circuit. The reactance of a transformer as transformers are generally constructed, while not absolutely uniformly distributed throughout the windings, changes substantially as the square of the number of turns; thus if the number of active turns of a given transformer are doubled, the reactance is increased about four times, and if the number of active turns are decreased the reactance is decreased in a corresponding manner. The per cent. reactance of such a transformer,

of course changes each time the reactance is changed, for the open circuit secondary voltage changes something like directly with the change in number of active turns. 55 By my invention, however, it is possible to vary the number of active turns of a transformer or analogous device without changing the per cent. reactance to the same extent as heretofore. It is possible even, as 60 indicated in the objects of my invention, to maintain the per cent. reactance at substantially one value throughout considerable changes in the number of active turns.

In general in transformers embodying my 65 invention, I divide the secondary winding into two portions to be connected in series, one of which is in closer inductive relation to the primary winding than the other and hence of lower reactance, and I preferably 70 provide for changing the number of turns in each group whenever the number of active turns is to be changed. The method of operation of my invention may be understood therefrom. This method comprises 75 making each change of voltage by changing the number of secondary turns by varying both the number of active secondary turns in poorer inductive relation to the primary and the number of active secondary turns in 80 closer inductive relation to the primary windings. Under some conditions it will be sufficient, however, in making each change in voltage to change only the number of secondary turns in closer inductive relation 85 to the primary windings as will appear hereinafter, the active secondary turns in poorer inductive relation to the primary windings being unchanged. By employing my invention the number of taps which may 90 be applied to any transformer is subject to considerably less limitations than heretofore.

In the above and hereinafter in the detail description of embodiments of my invention, and in the claims, I refer to primary and secondary windings. It will be understood, however, that I do this mainly for the sake of clearness and simplicity of description, and that in practice the windings I refer to as primary windings may, indeed, supply the load, the so-called sec-

ondary windings receiving energy from the supply lines.

My invention, as before indicated, is particularly applicable to those stationary 5 transformers used to supply series circuits from constant potential sources and which depend upon a considerable value of reactance to maintain the current supplied at something like a constant value irrespective of some changes in the load. Such 10 transformers are not capable of taking care of extreme changes in load without corresponding changes in the number of active turns, and heretofore such changes in turns 15 have involved considerable changes in the per cent. reactance of the device with corresponding changes in the regulation, the possible current on short circuit and the power factor. By employing my invention, 20 however, it is possible to provide a stationary transformer of the desired high reactance in which the number of active turns may be varied as desired over a wide range unaccompanied by such detrimental effects; 25 it is possible therefore to provide a single transformer which by means of taps is adapted to supply either relatively great or small loads and intermediate loads, all with substantially the same operating characteristics 30 so far as they are affected by the reactance of the transformer.

The accompanying drawings to which reference is hereinafter made, form a part 35 of this specification. Figure 1 is a diagrammatic illustration of a preferred form of transformer embodying my invention. Fig. 2 is a development of the windings of the transformer of Fig. 1, certain means for making the connections being diagrammatically 40 illustrated.

The transformer illustrated in these drawings is of high reactance; it is designed particularly for supplying series circuits and is required to supply more or less constant 45 current although itself supplied with substantially constant potential. While my invention is particularly applicable to this type of apparatus, some consideration will show that it is not limited thereto but it is 50 applicable to transformers of other types and for other purposes.

In practice the transformer I employ is substantially like that diagrammatically illustrated in Fig. 1. The core 3 is of the 55 center leg type, all the windings being assembled on the middle leg and the return for the magnetic flux being provided by external legs as indicated. The main secondary windings 4 comprise a plurality of 60 layers placed one above another; I have indicated the plurality of layers by the use of light and heavy lines. Taps, as 5 and 6, are provided in these windings as may be necessary; 7 and 8 are the terminals of these 65 windings. The primary windings 9 are

located in poor inductive relation to the main secondary windings 4, preferably at the end of the middle leg of the core remote from the main secondary windings 4. The auxiliary secondary windings 10 are located 70 in close inductive relation to the primary 9; preferably as indicated in heavy lines, they are located immediately below the primary windings; that is, between the primary windings and the core. A magnetic 75 shunt 11 is provided between the primary and auxiliary secondary windings on the one hand and the main secondary windings on the other; air gaps are left between the magnetic shunt and the core. The magnetic 80 shunt enables me to reduce somewhat the length of the core. The auxiliary secondary windings are preferably divided into two portions 12 and 13 electrically separated 85 from each other. Each portion is provided with such taps and terminals, 16—21, as may be necessary; as hereinafter indicated the tap, or taps, of the smaller of these two portions divides this portion into relatively small parts. In Fig. 2 the windings of the 90 transformer of Fig. 1 are developed, and for a further understanding of my invention reference may be had to Fig. 2 wherein the windings bear the same reference characters disposed in the same way as in Fig. 95 1, it being understood in considering Fig. 2 that considerable magnetic leakage is provided for between the primary windings 9 and the main secondary windings 4. This figure also diagrammatically illustrates 100 means 25 for connecting the taps and terminals of the secondary windings to the lines 26 and to each other in various arrangements.

It must be understood that each turn of 105 the windings of the drawings does not necessarily represent one turn in practice, but each turn of the drawing may represent a plurality of turns of a transformer constructed or operated in accordance with my 110 invention; for the purpose of this specification however, the relative numbers of turns between the various taps and terminals of the secondary winding may be regarded as something as indicated by the drawings. 115 The use of the terms "main secondary windings" and "auxiliary secondary windings" is not intended to indicate the relative numbers of turns in the main and auxiliary secondary windings. Both the numbers of 120 turns between the various taps and terminals and the relative numbers of turns in the main secondary windings and in the auxiliary secondary windings are subject to all the considerations of each particular case as 125 will be understood.

In varying the number of active turns according to my invention, preferably the number of active turns in both the main and auxiliary secondary windings are va- 130

ried. Suppose, for example, the load circuit for some particular load is attached to the tap 5 and the terminal 8 of the main secondary windings 4, the auxiliary secondary windings being inactive and not employed for this degree of full load. The load on the secondary circuit may be varied within certain limits without a material change in the current therein, for by reason of the high reactance of the transformer due to the location of the main secondary windings 4 with respect to the primary windings 9, the regulation is poor and the voltage impressed on the load circuit does not change proportionally to the load. This is the general plan of the action of certain simple so-called constant current transformers without moving parts. The range of action, that is the range throughout which the load may be varied without encountering an undesirable change in current, is however small and strictly limited unless some additional provisions are made for handling the major changes. Suppose now that the load on the transformer of Fig. 1 becomes or is about to become so great that the value of the current change is undesirable, that is, the current is established or is about to be established at an undesirably low value; in that case the number of active turns of the secondary windings must be increased to such an extent that the current through the load is again approximately the desired value. These increased active turns are preferably obtained partly by adding active turns to the main secondary windings 4 and partly by adding active turns to the auxiliary secondary windings 10; for example by connecting the load circuit to the terminal 8 of the main secondary windings 4 and to the tap 17 of the auxiliary secondary windings 10, the terminal 7 being connected to the tap or terminal 18. If now the transformer has been properly so designed, this change in the number of active turns is secured without a change in the per cent. reactance, and hence also without a change in the effect of the transformer on the power factor of the circuit supplying the primary windings, without changing the possible value of the current on short circuit and without affecting the regulation of the transformer. This may be regarded as due to the fact that the total reactance of the transformer has two components of different values, one determined by the main secondary windings 4 and the other by the auxiliary secondary windings 10. Both of these components are affected by the change in the number of active turns in such proportions that their resultant with respect to the voltage at the line terminals (that is the per cent. reactance) remains unchanged. When the transformer is essentially of high reactance as in the case illustrated, the number of turns varied

in the so-called main secondary windings will be greater in each instance than the number of turns varied in the auxiliary secondary windings at least where the per cent. reactance is to be held about constant.

If, however, it is found that the correction for the change in load is not quite right, another part, or other parts, of the secondary windings may be added or subtracted until the proper correction is made. For this purpose the taps (in the auxiliary secondary windings especially) divide the windings into unequal numbers or parts. For example, if the original correction is not far wrong, the part of the auxiliary secondary windings between the tap 20 and the terminal 21 (which is very small) may be connected in series with the load circuit, either bucking or boosting the remainder of the active secondary turns as the conditions require; in the former case the voltage impressed on the load circuit is reduced and the per cent. reactance increased, and in the latter case the load voltage is increased and the per cent. reactance reduced. If the proper correction is still to be found for this particular load, other slight changes may be made as by connecting the load circuit to the terminals 8 and 16 and connecting one or more parts of the auxiliary secondary windings 10 between the tap 19 and the terminal 21, in opposition between the tap 18 and the terminal 7. Thus by providing the auxiliary secondary windings with a number of taps preferably unequally distributed along its length, and preferably also providing for the connection of parts of those windings in opposition to other parts thereof as by the division of the auxiliary secondary windings 10 into separated parts, not only may the voltage and reactance be adjusted for considerable changes in load, but also the adjustment may be very accurately made in each case irrespective of the unavoidable errors in the design and construction of the transformer.

If, in the first case, instead of desiring to maintain the per cent. reactance at the same value as before the original change in the number of active turns, some increase in the per cent. reactance had been desired with the same increase in voltage, this could have been obtained by a few more turns between the tap 5 and terminal 7 of the main secondary windings 4 and a few less turns between the taps 17 and 18 of the auxiliary secondary windings 10. Likewise, the per cent. reactance might even have been decreased with the increase in the number of active turns by providing a few more turns between the taps 17 and 18 of the auxiliary secondary windings 10 and a few less between the tap 5 and terminal 7 of the main secondary windings 4. Thus it will be observed, by my invention the effect of

the change of number of active turns on the per cent. reactance of a transformer is subject to full control.

If the original load (connected between the terminal 8 and tap 5) is to be decreased, the decrease in total active turns is correspondingly accomplished by a decrease in the number of active turns in both the main and auxiliary secondary windings. Thus 10 the first step (the load before the change being connected between 8 and 5) may be by the connection of the load circuit leads to the terminal 8 and to the tap or terminal 18, the taps 6 and 17 being connected together. The portion of the auxiliary secondary windings between the taps 17 and 18 buck or oppose the main secondary windings and the effect is the same as though 15 some auxiliary secondary windings had previously been connected in series boosting with the main secondary and the number of active turns of said auxiliary secondary had been decreased with the decrease in active turns in the main secondary. As in the 20 previous case where the load and voltage were increased, more or less minor adjustments may be made by connecting a few more turns in series with the main secondary windings, either bucking or boosting the 25 voltage induced therein, and likewise the per cent. reactance may be varied as desired or held substantially constant.

Thus far the detailed description has related to a complete form of my invention, 30 and where this form is employed a single apparatus may serve loads subject to changes throughout a considerable range and the reactance may be very closely controlled. Where the range of load changes is less extensive, and particularly where the per cent. reactance may permissibly be subject to some slight changes with change in voltage, the simplified form of my invention suggested before may be employed. According 40 to this form of my invention each entire change in voltage is secured by changing only the number of active turns in the auxiliary secondary windings, the number of turns in the main secondary windings 45 remaining the same. Thus, referring again to Fig. 2 and contemplating only a load of three values, the load at intermediate value may be connected to the terminals 7 and 8 of the main secondary windings; the highest load which the transformer is adapted 50 to supply may be connected to the terminals 8 and 16, the taps 18 and 19 being connected together and the terminals 7 and 21 being connected together, the entire main 55 and auxiliary secondary windings being connected in series and boosting; the lowest load of the transformer may be connected to the terminals 8 and 21, the terminals 7 and 16 being connected together and the 60 65 taps 18 and 19 being connected together,

the main and auxiliary secondary windings being connected in series and bucking each other. Since the taps illustrated are not employed in this form of my invention, they may be omitted from apparatus designed 70 particularly for following this simplified form of my invention. It will be observed that when the auxiliary secondary windings are connected in series boosting with the main secondary windings and the voltage is 75 raised thereby, the per cent. reactance tends to remain at more nearly its original value than heretofore and may even assume a lower value than originally; also when these two windings are connected in series buck- 80 ing, the voltage is lowered without the usual great decrease in per cent. reactance, for the lower voltage has been obtained by adding active bucking turns (rather than subtracting turns) and the decrease in reactance is 85 due to propulsion of current through the auxiliary secondary windings in opposition to the voltage induced therein.

While I have described the principle of my invention and the best modes I have contemplated for applying this principle, other modifications will occur to those skilled in this art and I aim in the appended claims to cover all modifications which do not involve a departure from the spirit and scope 95 of my invention.

What I claim as new, and desire to secure by Letters Patent of the United States, is:—

1. The method of varying the voltage impressed on a circuit by means of inductively 100 related primary and secondary windings so wound on a closed magnetic core that certain secondary turns are in poorer inductive relation to the primary winding than other secondary turns, which consists in securing 105 the desired variation by varying both the number of active secondary turns in poorer inductive relation to the primary and the number of active secondary turns in closer inductive relation to the primary in such 110 manner as to secure both the desired voltage and a predetermined desired per cent. reactance.

2. The method of varying the voltage impressed on a circuit by means of inductively 115 related primary and secondary windings so wound on a closed magnetic core that certain secondary turns are in poorer inductive relation to the primary winding than other secondary turns, which consists in securing 120 the desired variation by varying both the number of active secondary turns in poorer inductive relation to the primary and the number of active secondary turns in closer inductive relation to the primary, the number of turns varied in poorer inductive relation being greater in each instance than the number of turns varied in closer inductive relation to the primary.

3. The method of varying the voltage im- 130

pressed on a circuit by means of inductively related primary and secondary windings so wound on a closed magnetic core that certain secondary turns are in poorer inductive relation to the primary winding than other secondary turns, which consists in securing each desired variation by varying both the number of active secondary turns in poorer inductive relation to the primary and the 10 number of active secondary turns in closer inductive relation to the primary in such manner as to secure both the desired voltage and a predetermined desired per cent. reactance, the two secondary groups being 15 connected in series.

4. The method of varying the voltage impressed on a circuit by means of inductively related primary and secondary windings so wound on a closed magnetic core that certain secondary turns are in poorer inductive relation to the primary winding than other secondary turns which consists in securing each desired variation by varying both the number of active secondary turns 25 in poorer inductive relation to the primary and the number of active secondary turns in closer inductive relation to the primary, the number of turns varied in poorer inductive relation being greater in each instance than 30 the number of turns varied in closer inductive relation to the primary, and the two secondary groups being connected in series.

5. The method of varying the voltage impressed on a circuit by means of inductively related primary and secondary windings wherein certain secondary turns are in poorer inductive relation to the primary winding than other secondary turns, which consists in securing each desired variation 40 by so varying the number of active secondary turns in poorer inductive relation to the primary and so varying the number of active secondary turns in closer inductive relation to the primary that the desired change in 45 voltage is secured and the total per cent. reactance of the inductively related windings is substantially unchanged.

6. A transformer comprising primary windings, main secondary windings so inductively related thereto as to provide for large magnetic leakage between the two, auxiliary secondary windings in closer inductive relation to the primary winding and means for connecting portions of said auxiliary and main secondary windings in series bucking or boosting.

7. A transformer comprising primary windings, main secondary windings inductively related thereto, auxiliary secondary windings in closer inductive relation to the primary windings and electrically separate from said main secondary windings, taps in the main secondary windings and taps dividing the auxiliary secondary windings 65 into portions of unequal numbers of turns,

the taps and terminals of said main and auxiliary secondary windings being brought out for interconnection and connection to the line in various arrangements.

8. A transformer comprising primary 70 windings, main secondary windings inductively related thereto, auxiliary secondary windings in closer inductive relation to the primary windings, the auxiliary secondary windings being divided into two electrically 75 separate major and minor parts, taps in the main secondary windings, taps in the major part of the auxiliary secondary winding, taps dividing the minor part of the auxiliary secondary winding into portions of unequal, 80 relatively small, numbers of turns, and means for connecting portions of said main and auxiliary secondary windings in series.

9. A transformer comprising primary 85 windings, main secondary windings inductively related thereto, auxiliary secondary windings in closer inductive relation to the primary windings and means for connecting portions of said main and auxiliary windings in bucking or boosting relations. 90

10. A transformer comprising primary windings, main secondary windings inductively related thereto, auxiliary secondary windings in closer inductive relation to the primary windings, a core of magnetic material interlinking said windings, and means for connecting a major portion of said main secondary windings alone to the line and for connecting said main and auxiliary secondary windings in series to the line. 100

11. A transformer comprising primary windings, main secondary windings inductively related thereto; auxiliary secondary windings in closer inductive relation to the primary windings, a core of magnetic material interlinking said windings, and means for connecting said main secondary windings alone to the line and for connecting said main and auxiliary secondary windings in series bucking or boosting to the line. 105

12. A transformer comprising primary windings, main secondary windings so inductively related thereto as to provide for large magnetic leakage between the two, auxiliary secondary windings in closer inductive relation to the primary windings, a core of magnetic material interlinking said windings, and means for connecting a major portion of said main secondary windings alone to the line and for connecting said main and auxiliary secondary windings in series to the line. 115

13. The method of varying the voltage impressed on a circuit by means of relatively stationary inductively related primary and secondary windings so wound on a closed magnetic core that certain secondary turns are in poorer inductive relation to the primary winding than other secondary turns, which consists in securing each de- 125 130

sired variation by varying the number of active secondary turns in closer inductive relation to the primary windings.

14. The method of varying the voltage impressed on a circuit by means of inductively related primary and secondary windings so wound on a closed magnetic core that certain secondary turns are in poorer inductive relation to the primary winding than other secondary turns, which consists in se-

curing each desired variation by varying such a number of active secondary turns in such closer inductive relation to the primary windings that the desired change in voltage is secured and the total per cent. reactance is 15 changed as desired.

In witness whereof, I have hereunto set my hand this 18th day of August, 1916.

SVEND E. JOHANNESEN.
